Fig. 4

FIGURE 1 is an elevational view of a container for dairy products or the like showing my new design;

FIGURE 2 is a bottom plan view thereof;

FIGURE 3 is a perspective view thereof; and

FIGURE 4 is a cross-sectional view thereof taken along the reference line 4-4 of FIGURE 1.

The essential features of my design are indicated by solid lines and reside in the configuration of a band around a lower part of a container, the band having a plurality of parallel relatively narrow vertical strips separated by relatively wide spaces, the spaces defining flat surfaces joined by a bevel portion with an upper part of said container.

I claim:
